W. H. LARAWAY

VENDING MACHINE

Filed Dec. 14. 1921

5 Inventor
William H. Laraway

By

Orville J. Biley

Attorney

UNITED STATES PATENT OFFICE.

WILLIAM H. LARAWAY, OF GRAND RAPIDS, MICHIGAN.

VENDING MACHINE.

Application filed December 14, 1921. Serial No. 522,437.

To all whom it may concern:

Be it known that I, WILLIAM H. LARAWAY, a citizen of the United States, residing at Grand Rapids, in the county of Kent and 5 State of Michigan, have invented certain new and useful Improvements in Vending Machines, of which the following is a specification.

My invention relates to improvements in 10 vending machines, and its objects are: first, to provide a means whereby the operation of the machine will be absolutely positive and will insure proper delivery of goods; second, to provide a means whereby the 15 working of the machine is absolutely under the control of the operator, and, third, to provide a means whereby the movements of the actuating levers and other like mechanism may be regulated to a nicety.

20 I attain these objects by the mechanism shown in the accompanying drawing, in which Fig. 1 is a front elevation of the machine. Fig. 2 is a side elevation and Fig. 3 is a transverse sectional elevation of 25 the same. Fig. 4 is a vertical section of the lower part of the machine on the line 4—4 of Fig. 5. Fig. 5 is a like view on the line 5—5 of Fig. 4. Fig. 6 is a perspective of 30 the actuating lever. Fig. 7 is a like view of the slide that discharges the goods being sold. Fig. 8 is a plan of the adjusting bar, and Fig. 9 is a plan of the stationary chute.

Similar reference characters indicate similar parts throughout the several views.

35 My invention consists in an enclosing case 1 having a glass frame 2 and glass 3 in the front of the upper part of the machine, with a back 5 and partition bars 4, arranged to form chutes for the packing and free movement of perfume bottles 22, for the sale of 40 which this particular machine is designed.

In operation the perfume bottles are placed in the receiving chute and are supported upon a foundation *b*, within the opening *a* in the slide 7. This slide is provided with an arm 8 that extends backwardly in position to press against the surface of the actuating lever 16, and is held in place by means of a spring, as *i*, which holds the 50 slide, temporarily, in normal position to receive the bottles in the opening *a*. In front of the slides I place a cover 9 and a floor 10 in position to form a discharge chute 11 for the discharge of the bottles.

55 The floor 10 has slot openings *f* through it for the passage of coin into the coin

chute 17, which is provided with a slot *g* for the free passage of the coin *m* into the upper end of the slot *d* in the actuating lever 16. This lever is pivotally mounted upon 60 the case, as at *e*, so when a coin has been carried into the slot *d* immediately back of the operating bar 18, which is mounted upon a shaft 15, and the free edge of this bar is forced downwardly with the lever 14 the 65 coin will be made to roll downwardly and will force the lower end of the lever 16 backwardly, thus forcing the upper end of this lever forwardly against the end of the arm 8, thus forcing the slide 7 forwardly 70 sufficiently to allow the bottles to drop out of the opening *a* and off of the support *b* onto the floor 10 within reach of the operator. The actuating bar 18 is returned 75 into normal position by means of a spring, 75 as 19, and the throw of the lever 16 is adjusted by means of the adjusting bar 20 and the adjusting screws 21 acting upon the bearing *n* on the lower end of the lever 16. The function of the adjustable screw 21, is 80 to adjust the distance of the lever 16 relative to the bar 18 to correspond with the diameter of different coins, as nickels, dimes, cent pieces, etc.

To secure the front of the machine into 85 the case the front piece 12 is hinged to the bottom of the case, as at 13, with the roof 9 and the floor 10 firmly secured thereto and bearing against the lower end of standards or partitions 4, when the upper front 90 2 is put into place and locked to the roof 9 by means of a lock at *o* in Fig. 1.

When desiring to purchase a bottle of perfume from the machine the operator drops a coin through the slot *f*, and the coin rolls 95 into the position indicated at *m* in Fig. 4, when the lever 14 is forced over in the direction indicated by the arrow in Fig. 1, when the lever 16 is actuated to force the slide 7 far enough forward to allow a 100 bottle to drop off of the support *n* onto the floor 10 into position where it can be readily taken by the operator, when the lever is released and the bar 18 is returned to normal position by the spring 19, as hereinbefore stated.

Having thus fully described my invention, what I claim as new in the art, is:

1. In combination with a case having chutes therein for storing bottles in vertical tiers, a slide under each chute for forcing the lower bottles from the chutes out of the 110

machine, an inclined roof below said slides having slots therethrough and slotted chutes for the passage of coin to its actuating mechanism; a lever pivotally mounted in the case before each bottle chute with a slotted downwardly extended body, and an upwardly extending arm, an actuating bar adjacent to each slotted body and pivotally mounted at a point distant from the body and so positioned that it may be thrown forwardly and downwardly to revolve the coin in the slot and force the body of the lever backwardly, and the arm of the lever forwardly, a backwardly extended arm on each slide so contacting the arm

on the lever that the forward movement of the arm will force the slides forwardly and discharge a bottle therefrom, an actuating spring for carrying each slide back into normal position.

2. In combination with the elements covered in claim 1, a spring for carrying the actuating bar back into normal position, and an adjusting bar and screws for adjusting the movements of the actuating levers.

Signed at Grand Rapids, Michigan, December 6, 1921.

WILLIAM H. LARAWAY.
